UNITED STATES PATENT OFFICE.

CHARLES J. GRAYSON, OF ASHLAND, KENTUCKY.

DESIGN FOR A HEATER.

Application filed December 21, 1923. Serial No. 8,117. Term of patent 3½ years.

To all whom it may concern:

Be it known that I, CHARLES J. GRAYSON, a citizen of the United States, residing at Ashland, in the county of Boyd and State of Kentucky, have invented a new, original, and ornamental Design for Heaters, of which the following is a specification, reference being had to the accompanying drawing, forming part thereof.

The figure is a perspective view of a heater showing my new design.

I claim:

The ornamental design for a heater as shown.

CHARLES J. GRAYSON.
